UNITED STATES PATENT OFFICE

JOHN H. McDEVITT, OF CULPEPER, VIRGINIA

GATE

Application filed November 4, 1929. Serial No. 404,705.

This invention relates to a gate particularly adapted for use in connection with motor vehicular traffic and has for its primary object to provide, in a manner as hereinafter set forth, a gate of such class which is normally latched in closed position and which may be opened by the contact of a vehicle approaching from either direction with a latch releasing means carried by the gate.

10 A further object of the invention is to provide a gate of the character aforesaid which is provided with means for automatically closing the gate after the passage of the vehicle therethrough.

15 A further object of the invention is to provide a gate of the character aforesaid in which the latch releasing means is disposed vertically in order that the same may be operated by a man on horseback.

20 With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the 25 scope of the claims hereunto appended.

In the accompanying drawings in which like numerals are employed to designate like parts throughout the same:

30 Figure 1 is an elevation of a gate in accordance with this invention.

Figure 2 is a top plan thereof.

Figure 3 is a horizontal section thereof.

Figure 4 is a section taken on the line 4—4, 35 Figure 2.

Figure 5 is a section taken on the line 5—5, 40 Figure 2.

Figure 6 is a section taken on the line 6—6 of Figure 1.

45 Referring to the drawings in detail, the numerals 1 and 2 designate a support post and a latch post respectively which are adapted to be disposed on opposite sides of a driveway. Disposed between the posts 1 and 2 is a gate structure which includes a vertically disposed end member 3 which is hinged to

the post 1 by means of a vertical rod 4 which extends through a pair of spaced eye forming members 5 projecting from the member 3 and through a similar pair of eye forming members 6 projecting from the post 1. Secured at their inner ends to the member 3 is a plurality of spaced, horizontal members 7, the outer ends of which are secured to a pair of vertically disposed end members 8 disposed on opposite sides of the horizontal members 7. Substantially midway between the end members 8 and 3 is a pair of vertical brace members 9 which are similar to the end members 8 and which are disposed on opposite sides of the horizontal members 7. Extending from the brace members 9 to the end member 3 is a pair of diagonally disposed brace members 10 which are disposed on opposite sides of the horizontal members 7 and which are fixedly secured thereto.

50 Disposed between the brace members 9 and end members 8 is a pair of trip boards 11 which are connected with the brace members 9 by means of hinges 12. The trip boards 11 are arranged to extend in a vertical direction with the upper ends thereof extending above the upper ends of the brace members 9 and the trip boards 11 are connected together adjacent their upper ends by means of a chain 13.

55 Extending from the opposing faces of the trip boards 11 are pins 14, one of which is located above the other, and which cross each other adjacent their free ends. Extending longitudinally of the gate structure, and slideable between the braces 9 and end members 8, is a latch bar 15, the outer end of which is adapted to be received between a pair of oppositely disposed latch members 16 pivoted intermediate their ends to the latch post 2. 60 The pivots 16' for the latch member 16 are disposed between the centers and the outer ends of the latter whereby the inner ends of the members 16 will normally tend to swing about the pivots 16' in downward arcs. Outwardly and upwardly spaced from the pivots 16' are stops 17' against which the outer end portions of the members 16 abut when the inner ends of the latter are swung to their 65 downward positions. The inner end edges 70

of the members 16 are beveled as indicated at 18' whereby such edges are disposed vertically when the members 16 are in abutment with the stops 17', and the members 16 are of 5 appropriate length to position the vertical edges 18' in spaced relation for the reception of the outer end of the latch bar 15 therebetween.

Projecting from the upper face of the latch 10 bar 15 is a pin 17 for engagement with the pins 14 carried by the trip boards 11. The latch bar 15 is normally held with the outer end thereof projecting between the vertical edges 18' of the latch members 16 by means 15 of a spring 18 which extends longitudinally of the latch bar 15 and the ends of which are connected with the latch bar and with the end members 8. When the latch bar 15 is in latching position, the pin 17 is drawn 20 forcibly against the pins 14 whereby the free longitudinal edges of the trip boards 11 are forced away from each other as illustrated in Figure 2.

The latch bar 15 is normally maintained in 25 alignment with the space between the vertical edges 18' of the latch members 16 by means of a pair of springs 19, the inner ends of which are secured to one of the horizontal members 7, and the outer ends of which are 30 connected, by means of a pair of turnbuckles 20, with an elongated supporting element 21 which is rigidly secured to the supporting post 1 and which extends in parallel relation to the driveway. The turnbuckles 20 are ad- 35 justed in a manner to provide the springs 19 with equal tension whereby the gate structure will be normally extended between the posts 1 and 2 with the latch bar 15 in alignment 40 with the space between the vertical edges 18' of the latch members 16.

When it is desired to operate the gate to open the same by the contact of a vehicle therewith, the vehicle is driven against one of the trip boards 11 whereby the free edge of 45 such trip board will be swung towards the horizontal members 7 as indicated in Figure 3. Such movement of the trip boards 11 causes the pin 14 carried thereby to force the latch bar 15 out of engagement with the latch members 16 by the engagement of the pin 14 with the pin 17 after which the gate may be 50 swung to open position by driving the vehicle between the posts 1 and 2. In order to prevent any likelihood of the vehicle fouling the 55 operation of the latch bar 15, a protecting element such as a screen 23 is provided on either side of the latch bar. The screens 23 extend from the end members 8 to a point adjacent the trip boards 11 and are fixedly secured to 60 the horizontal members 7 and the end members 8. Preferably a bumper 24 is secured to the outer face of each of the end members 8 to prevent the finish of the vehicle from being marred by the end members 8 as the vehicle 65 passes the same.

When the gate is swung to closure position by means of the springs 19, the outer end of the latch bar 15 is caused to ride under the nearest latch member 16 in contact with the lower face of the latter whereby the inner 70 end of such latch member will be swung about its pivot in an upward arc. As soon as the latch bar 15 has cleared the inner end of such latch member, the inner end of the latter will be returned by gravity to its normal position 75 and the outer end of the latch bar 15 will be positioned between the opposing inner ends of the latch members 16, thereby latching the gate in closure position until the latch bar 15 is moved longitudinally to remove the outer 80 end thereof from the space between the vertical edges 18.

When approaching the gate on horseback, the gate may be opened by grasping one of the trip boards 11 adjacent its upper end and 85 forcing the free edge thereof towards the horizontal members 7 whereby the latch bar 15 will be removed from engagement with the latch members 16 in the same manner as heretofore described. As soon as the object 90 passing through the gate has become disengaged therefrom, the same will be returned to closure position by means of the springs 19.

It is thought that the many advantages of 95 a gate in accordance with this invention will be readily apparent, and although the preferred embodiment of the invention is as illustrated and described, yet it is to be understood that changes in the size, shape and arrangement of parts may be resorted to, so long 100 as such changes fall within the scope of the invention as defined in the appended claims.

What I claim is:

1. In a gate structure, the combination of a latch post, a swinging gate adjacent the latch post, a latch bar slidably mounted on the gate, latching means on the latch post for engagement by said latch bar, yielding means normally holding the latch bar in engagement with said latching means, vertically disposed trip boards mounted on opposite sides of the gate to swing on vertical axes, and coacting means carried by the latch bar and trip boards for normally extending the free vertical edges of the trip boards from the gate 110 when the latch bar is in latching position, said coacting means operating to disengage said latch bar from said latching means when the free vertical edges of one of said trip boards are moved towards the gate, said trip boards extending throughout the entire height of the gate and projecting above the latter.

2. In a gate structure, the combination of a latch post, a swinging gate adjacent the latch post, a latch bar slidably mounted on the gate, latching means on the latch post for engagement by said latch bar, yielding means normally holding the latch bar in engagement with said latching means, vertically disposed 125

trip boards mounted on opposite sides of the gate to swing on vertical axes, and coacting means carried by the latch bar and trip boards for normally extending the free vertical edges of the trip boards from the gate when the latch bar is in latching position, said coacting means including a pair of pins projecting horizontally from the trip boards and disposed in intersecting relation, and a stud projecting vertically from the latch bar in contacting relation with said pins, each of said pins operating to disengage said latch bar from said latching means by the engagement of the pin with the stud when the free vertical edge of the trip board from which such pin projects is moved towards the gate.

In testimony whereof, I affix my signature hereto.

JOHN H. McDEVITT.
